UNITED STATES PATENT OFFICE.

WILLIAM O. PEAVEY, OF EBRO, MINNESOTA.

SPIKE-PULLER.

1,364,451.

Specification of Letters Patent.

Patented Jan. 4, 1921.

Application filed October 24, 1919. Serial No. 332,902.

To all whom it may concern:

Be it known that I, WILLIAM O. PEAVEY, a citizen of the United States, residing at Ebro, in the county of Clearwater and State 5 of Minnesota, have invented certain new and useful Improvements in Spike-Pullers; and I do hereby declare the following to be a full, clear, and exact description of the invention, such as will enable others skilled in the art to which it appertains to make and 10 use the same.

This invention relates to spike pullers and the primary object of the invention is to provide an improved device especially adapted 15 for pulling railroad spikes, and so formed, that a firm grip may be obtained on the head of the spike and the spike readily pulled, with very little effort.

Another object of the invention is to provide 20 an improved railroad spike puller having means formed thereon, for engaging the flange and web of a rail, so that the spike may be readily lifted.

A further object of the invention is to provide 25 an improved spike puller embodying a pivoted support adapted to engage a tie or other object in which the spike is inserted, so as to form means for elevating the puller, after the spike has been raised a certain distance out of the tie.

A still further object of the invention is to provide 30 an improved railroad spike puller of the above character, which is durable and efficient in use, one that is simple and easy to manufacture, and one that can be placed upon the market at a reasonable cost.

With these and other objects in view, the invention consists in the novel construction, arrangement, and formation of parts as will 40 be hereinafter more specifically described, claimed and illustrated in the accompanying drawings, forming a part thereof, in which—

Figure 1 is a side elevation of the improved tool, showing the same in operative 45 position and engagement with a railroad rail,

Fig. 2 is a top plan view of the same,

Fig. 3 is a vertical longitudinal section 50 through the same,

Fig. 4 is a transverse section taken on the line 4—4 of Fig. 1,

Fig. 5 is a detail bottom plan view of the head of the device, and,

Fig. 6 is a side elevation showing the pivoted support in operative position.

Referring to the drawings in detail, where-

in similar reference characters designate corresponding parts throughout the several views, the numeral 1 generally indicates the improved spike puller, which includes the 60 circular head 2 and a handle 3 which extends outwardly from the curved face of the head and which is curved upwardly as at 4 so that the same can be readily grasped and actuated. The lower face of the head is provided with a cut-out portion 5 which gradually increases in depth toward the upper end thereof to form an abrupt shoulder 6. The head has secured thereto on its opposite sides 65 circular plates 7 which are held in place by 70 suitable spaced bolts 8. The plates, as clearly shown in Fig. 4 of the drawings, extend downwardly on each side of the cut-out portion and are provided with inwardly extending flanges 8' for engaging under the 75 head of the spike. The plates 7 and the head are provided with an eccentric opening 10 which receives the pivot bolt 11 on which is secured the tie engaging support 12, which will be hereinafter more fully described. 80 The head 2 is provided with an outwardly extending tangentially disposed lip 13 which is adapted to engage the flange or ball of the rail, to form means, whereby the spike may be readily elevated, after the head of the 85 same has been inserted between the plates 7.

In operation of the improved device, the flanges 8' are first engaged with the under-side of the head of a spike and the handle is then grasped and moved upwardly, and 90 forwardly. Upon this movement of the handle, the spike will be elevated owing to the head coming into engagement with the tie. When the spike has been elevated a certain distance, the lip 13 will be placed 95 into engagement with the flange of the rail and the handle moved upwardly which will further elevate the spike. If the spike is of extra length the lip 13 may be placed into engagement with the ball of the rail to further pull the same outward of the tie. When extra long spikes are to be pulled the pivoted support 12 is brought into play and the same includes the triangular shaped side wings 20 the bases of which form means 100 for engaging the tie or ground. The wings 20 are clutched together adjacent the outer ends thereof and connected at one edge by a wall 21, which is adapted to engage the upper surface of the handle to limit the 105 downward movement of the side wings, and hold the same in inoperative position.

From the foregoing description, it can be seen that an improved spike puller is provided, so constructed as to readily and quickly pull a spike from the tie.

5 In practice, I have found that the form of my invention illustrated in the accompanying drawings and referred to in the above description, as the preferred embodiment, is the most efficient and practical; yet 10 realizing the conditions concurrent with the adoption of my device will necessarily vary, I desire to emphasize that various minor changes in details of construction, proportion and arrangement of parts may be resorted to, when required without sacrificing any of the advantages of my invention as 15 set forth.

What I claim as new is:—

20 1. A spike puller comprising a circular head, a handle secured to and extending outwardly from the curved face of the head, said curved face having a spike head receiving groove formed in its lower side, and spike head engaging flanges located within 25 said groove.

2. A spike puller comprising a circular head, a handle secured to the head and extending outwardly from the curved face thereof, the head having a spike head receiving groove formed therein gradually decreasing in depth toward the handle, and an outwardly extending lip formed on the head opposite to the handle arranged to engage the ball or flange of a rail. 30

35 3. A spike puller comprising a circular

head having a cut-out portion formed in the lower surface thereof gradually increasing in depth toward one end, an outwardly extending handle formed on the head above and in rear of the cut-out portion, circular plates bolted to the opposite sides of the head and extending below each side of the cut-out portion, said plates having inwardly extending ribs gradually increasing in width toward the increased end of the 40 cut-out portion for receiving the spike head, as and for the purpose specified. 45

4. A spike puller comprising a circular head, an outwardly extending handle carried by the head, said head having a cut-out portion formed therein gradually increasing in depth toward one end thereof, plates secured on opposite sides of the head and extending below the cut-out portion, inwardly extending ribs formed on the lower edges 55 of the plates adjacent the cut-out portion of the head, an outwardly extending lip formed on the head above said cut-out portion, and a pivoted support carried by the head and arranged to engage the tie including side wings and a connecting portion adjacent to the outer end thereof, as and for 60 the purpose specified.

In testimony whereof I affix my signature in presence of two witnesses.

WILLIAM O. PEAVEY
